PAINT ROLLER SCRAPER

Andrew J. Basala, Jr., Detroit, Mich.

Application May 5, 1955, Serial No. 506,294

5 Claims. (Cl. 15—236)

This invention relates to a paint roller cleaning device, and, more particularly, to a paint roller cleaning device which is adapted to clean a paint roller by means of a combined squeezing and scraping action.

In recent years, the use of paint rollers has increased considerably, and, the cleaning of the roller after the paint job has been completed presents the person using the roller with a time consuming and unpleasant task. Accordingly, it is the primary object of this invention to provide a paint roller cleaning device which is adapted to clean a paint roller quickly and efficiently.

It is another object of this invention to provide a paint roller cleaner which is small in size and light in weight, and which is easy to use.

It is another object of this invention to provide a paint roller cleaner which is rugged in construction, and economical of manufacture.

It is a further object of this invention to provide a paint roller cleaning device which includes a pair of oppositely disposed arcuate members adapted to be moved into engagement with the paint roller to be cleaned, in an encircling fashion, and a handle means for biasing said arcuate members into engagement with the roller.

Other objects, features and advantages of this invention will be apparent from the following detailed description and appended claims, reference being had to the accompanying drawing forming a part of the specification, wherein like reference numerals designate corresponding parts of the several views.

In the drawing:

Fig. 1 is a side elevational view of an illustrative embodiment of the invention;

Fig. 2 is a top plan view of the structure illustrated in Fig. 1;

Fig. 3 is a side elevational view of a second embodiment made in accordance with the principles of the invention;

Fig. 4 is a top plan view of the structure illustrated in Fig. 3;

Fig. 5 is a fragmentary perspective view of the structure illustrated in Fig. 4, taken along and within the circle marked 5; and,

Fig. 6 is a perspective view of a paint roller upon which the embodiment of Fig. 1 is shown in an operative position.

Before explaining in detail the present invention, it is to be understood, that the invention is not limited in its application to the details of construction and arrangement of parts illustrated in the accompanying drawing, since the invention is capable of other embodiments and of being practiced or carried out in various ways. Also, it is to be understood, that the phraseology and terminology employed herein is for the purpose of description and not limitation.

In the drawings, a first embodiment of the invention is shown in Figs. 1 and 2, which comprises a paint roller cleaner formed from a single elongated piece of flat strip metal, or the like, which has been bent into a U-shape

2

with a bight portion designated as 10. Extending forwardly from the bight portion 10 are the two handle portions 12 and 14. Integrally connected to said handle portions, at the points 16 and 18, are a pair of arcuately shaped, roller engaging arms 20 and 22, respectively, which are oppositely disposed so as to form a substantially circular area therebetween. As best seen in Fig. 1, the arms 20 and 22 are disposed in a plane at substantially right angles to that of the handle portions 12 and 14.

The outer ends of the arms 20 and 22 overlap each other. The outer end of the arm 20 is folded back on itself, as indicated by the numeral 26, with the fold being along an approximate 45° angle. The arm end 26 is then folded over the outer end of arm 22, as shown by the numerals 28 and 30, to form a U-shaped slot or retaining means for retaining the arm end 32 always adjacent the arm 20 during a cleaning operation. The U-shaped retaining means 28 and 30, prevents the arms 20 and 22 from moving apart from each other, in a lateral direction, during use thereof.

The use of the embodiment of Fig. 1 is illustrated in Fig. 6, wherein is shown a paint roller apparatus handle 34, which carries a frame structure generally indicated as 36 on which is mounted a paint roller shaft 38. Rollably mounted on the shaft 38 in the usual manner is a paint roller 40. After completing a paint job with the paint roller 40, the embodiment of Figs. 1 and 2 would be slipped over the free end of the paint roller 40. This action is possible because when not in use, the handle portions 12 and 14 will spring outwardly, thus moving the arcuate arms 20 and 22 apart so that the device will easily slip around a paint roller. After the device has been slipped around the roller 40, the paint thereon may be removed by squeezing inwardly on the handle portions 12 and 14, so as to bring the arms 20 and 22 into a tight engagement with the roller, and then moving the device to the right or left, as viewed in Fig. 6. The paint on the roller will be squeezed off onto the cleaning device, as the arms are moved inwardly, and a scraping action will also be effected when the device is moved lengthwise of the roller 40. It has been found, that this novel squeezing and scraping action provides a quick and efficient cleaning result on a dirty paint roller.

In Figs. 3 through 5, there is illustrated a second embodiment of the invention which is made from a suitable single, elongated rod-shaped metal, or the like. As best seen in Figs. 3 and 4, the round stock, or rod, would be turned and coiled back on itself to form a spring bight portion 42, which is integral with a pair of spaced apart handle portions 44 and 46. The handle portions 44 and 46 are preferably flattened, as at 48 and 50, respectively, to form thumb and finger pressure rests or grips. The rods would be arcuately formed, from the forward ends of the handle portions 44 and 46, as indicated at the points 52 and 54, respectively. The arcuately formed rod portions would form a pair of oppositely disposed arms 56 and 58, similar to the arms 20 and 22 of the embodiment of Figs. 1 and 2.

The outer end of the arm 56 is curved upwardly and then is folded over on itself, as shown at 62 and 64, to form a U-shaped retainer, to retain the outer end 66 of the other arm 58 in close sliding relation to the arm 56. The arcuate arms 56 and 58 are flattened, and, they are similar in shape to the arms 20 and 22, of the embodiment of Fig. 1. The embodiment of Figs. 3 and 4 would be used in the same manner as the embodiment of Figs. 1 and 2.

While it will be apparent that the preferred embodiments of the invention herein disclosed are well calculated to fulfill the objects above stated, it will be appreciated that the invention is susceptible to modification, variation

and change without departing from the proper scope or fair meaning of the subjoined claims.

What is claimed is:

1. A paint roller cleaning device of the class described, comprising: a single length of flat strip material including a U-shaped portion medially between the opposite ends of said length of material, and a pair of elongated handles having the rear ends thereof integral with the opposite ends of said U-shaped portion; said handles being normally spaced apart; a pair of semi-circular arms integral with the front ends of said handles and being disposed in confronting relation for gripping of said paint roller therebetween and for squeezing of the paint roller responsive to movement of the handles against the restraint of the U-shaped portion and to movement of the device lengthwise of the paint roller; and each of said arms having a flat face disposed in a plane normal to the plane of the flat surface of the respective handle with which it is integral, whereby, the paint squeezed from the paint roller will not slide back over the arms when the device is moved lengthwise of the paint roller.

2. The invention as set forth in claim 1, wherein: the front ends of the arms are slidably interconnected.

3. The invention as set forth in claim 1, wherein: the front end of one of said arms is provided with a laterally extended U-shaped member in which the front end of the other of said arms is slidably interconnected.

4. A paint roller cleaning device of the class described comprising: a pair of arcuate arms; said arms being disposed so as to form a substantially circular structure; said

arms being flattened in a plane normal to the axis of the circle formed by said arms; a handle connected to the rearward end of each of said arms, whereby, said arms may be manually moved into engagement with the circular surface of a paint roller for scraping and squeezing the paint therefrom; each of said handles being provided with a flat finger rest adjacent the forward end thereof; the forward ends of said arcuate arms being slidably interconnected; and, the outer ends of said handles being integrally joined by a means which normally biases said handles apart to a position of rest.

5. The invention as set forth in claim 4, wherein: the forward end of one of said arcuate arms is provided with a laterally extending U-shaped extension in which the forward end of the other arcuate arm slides to provide said slidable interconnection.
